UNITED STATES PATENT OFFICE.

ALFRED JAMES WESTON, OF TORONTO, ONTARIO, CANADA.

PORTABLE CURTAINED HAMMOCK-STAND.

SPECIFICATION forming part of Letters Patent No. 427,490, dated May 6, 1890.

Application filed October 9, 1889. Serial No. 326,449. (No model.)

To all whom it may concern:

Be it known that I, ALFRED JAMES WESTON, builder, of the city of Toronto, in the county of York, in the Province of Ontario, Canada, have invented a certain new and Improved Portable Curtained Hammock-Stand, of which the following is a specification.

The object of the invention is to design a comfortable curtained hammock-stand which may be readily taken apart and packed into a small compass; and it consists, essentially, of two vertical posts provided with lateral braces and connected together by two rails detachably connected to the posts from which the hammock is suspended, curtains being hung from the top rail on either side of the hammock.

Figure 1 is a perspective view of my improved hammock-stand with one of the curtains removed. Fig. 2 is a view of my hammock-stand packed for shipping.

The two vertical posts A are each provided with a pair of lateral braces B, which are preferably hinged at a to their respective posts, and are further connected to them by the hinged arms C.

D is the upper rail, on each end of which a projecting finger E is fixed, which finger is designed to fit into a socket F, fixed to the posts A, as shown.

G is the lower rail, which is connected to the posts A in the same manner as the upper rail

D. When the rails D and G are placed in position, as indicated in Fig. 1, they securely brace the two posts A together, while the lateral braces B constitute substantial side supports. On each side of the rail D, I fix suitable rods H, on which the rings attached to the curtains are placed. The hammock K is suspended from the hooks L, fixed to the posts A, as indicated.

In order to pack the hammock-stand into a small space to facilitate its transportation, the rails D and G are knocked out of their sockets, the curtains I wrapped round them and the rails placed parallel with the posts A and the whole bound together by the straps J, as shown in Fig. 2, the hinged arms C being disconnected, as indicated.

What I claim as my invention is—

A hammock-stand consisting of the standards having hooks for the hammock and carrying socket-pieces at their upper and lower ends, inclined braces hinged to said standards, the rails having fingers fitting in said sockets, and rods secured to the upper rail on each side thereof to receive the rings on the curtain.

Toronto, September 10, 1889.

ALFRED JAMES WESTON.

In presence of—

CHARLES C. BALDWIN,
I. EDW. MAYBEE.
